UNITED STATES PATENT OFFICE

ANDREAS C. NIELSEN, OF EAST CLEVELAND, OHIO

TOOTHBRUSH

Application filed October 10, 1928. Serial No. 311,515.

The object of this invention is to provide an improved collapsible brush especially adapted for a tooth brush which can be carried in a small space when traveling.

- 5 The construction described herein is adapted for a tooth brush of any desired type with a short, smooth tapered shank for attaching to the combination handle and holder or casing.
- 10 It will be noted that the need of attachments to or irregularities in the surface of said shank is avoided thus making it more sanitary and less expensive to manufacture.

The aforementioned combination handle 15 and holder is so designed as to be made of one piece of material thus avoiding expensive, troublesome and unsanitary hinges or the use of loose pieces which are liable to be mislaid or lost. Moreover, all parts are 20 readily available for cleansing.

In the accompanying drawings:

Fig. 1 is a top view of a collapsible tooth brush made according to this invention.

Fig. 2 is a side view of Fig. 1.

25 Fig. 3 is a side view of the brush in collapsed position.

Fig. 4 is an end view of Fig. 3.

Fig. 5 shows the brush in an inverted position in the holder.

30 Fig. 6 is a top view of a modification.

Fig. 7 is a side view of Fig. 6.

Referring specifically to the drawings—a tooth brush 1 of familiar construction has a short shank 2 with one surface 3 tapered with 35 respect to the opposite side thereof. While it is shown as having a rectangular cross section, I do not limit myself to the cross section shown because a great variety of cross sections could be used provided there was one 40 tapered surface as described. Said shank 2 is inserted in a coacting socket 4 in the holder or handle 5.

Said holder 5 is made conveniently of a piece of sheet metal, celluloid, plastic or 45 other material bent to form the socket 4 and having the meeting edges welded, cemented or otherwise attached as indicated at the line 6 in Fig. 4. There is also a pin 7 which is likewise welded, riveted, cemented or otherwise secured in the holder 5 in such a posi-

tion as to engage with the tapered surface 3 of the shank 2. It will readily be seen that a slight pressure applied to the brush when it is inserted in the position shown in Figs. 2, 3 and 5, will cause the shank 2 to be held in 55 a gripping manner in the socket 4 and by the pin 7. The end 8 of the shank 2 projects through the socket sufficiently far so that pressure can be applied to said projecting end 8 when it is desired to release the brush from 60 the holder, thus making it more convenient to operate.

When the parts of the holder 5 are made integrally as above described a holder is produced which has no moving parts and all 65 surfaces are readily accessible for cleaning. A further advantage of compactness is secured in this construction because no space is taken by a cover over the back of the brush since the back of the brush itself is used to 70 form the cover of the enclosure for the bristles 9, also with this construction less space need be provided in the container as space is provided for the bristles only holding the bristle holder or back of the brush outside, 75 serving as cover or lid. A still further advantage to be pointed out is that the open side and cutaway portion 10 of the holder 5 near the socket 4 provides a convenient means for gripping the brush to remove it from its holder (see Fig. 3), after it has first been loosened by pressure against the end 8 of the shank 2.

As an aid in placing the bristles within the holder 5, the mouth 11 thereof is made flaring, and this also has the added advantage 85 of strengthening and bracing this portion of the structure.

The same flaring mouth will be noted at 12 in Fig. 6 which is a convenient modification in case it is desired to cut the holder 13 out 90 of a solid piece of material or to mold it of plastic material. In such a case various portions may be removed to reduce the amount of material and holes 14 may be added if desired for hanging up the brush unfolded as 95 shown in Figs. 2, 6 and 7.

As will be seen, the holder 5 is hollow so that when the brush is collapsed the bristles are held and protected between the flat side walls of the holder, and the back 1 of the 100

brush rests upon the edge of these side walls, as shown in Figs. 3 and 4 so that the bristles are not bent and cannot be pressed into contact with the bottom of the holder, but remain in straight or extended position so that they will dry in straight position and sufficient ventilation is afforded to insure quick drying while at the same time the bristles are protected from contact with adjacent articles when the brush is packed for transportation.

10 While I have shown and described certain forms of the invention obviously various embodiments may be made together with changes in the details of construction, falling within the spirit of the appended claims.

15 I claim:

1. A tooth brush comprising a hollow handle substantially U-shaped in cross section and having a socket at one end thereof open at 20 both ends and a pin extending across between the sides of the handle, and a brush portion having a shank adapted to be entered into either end of the socket and engaged against the pin, the bristles of the brush being enclosed between the sides of the handle when 25 the shank is inserted into the inner end of the socket.

2. A tooth brush as in claim 1, the back of the brush portion resting against the edges 30 of the sides of the handle when the shank is inserted into the inner end of the socket.

35 In testimony whereof, I do affix my signature.

ANDREAS C. NIELSEN.
